(57) **CLAIM**

The ornamental design for a sprayer shroud, as shown and described.

DESCRIPTION

In a preferred embodiment the nature of this product is as a shroud suitable to cover a trigger sprayer pumping apparatus.

FIG. 1 is a left, top, front perspective view of a sprayer shroud embodying our new design;

FIG. 2 is a left, side elevational view thereof, the right side elevational view thereof being a mirror image of the left side elevational view shown;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a left side elevational view thereof, albeit with typical associated environment depicted as well.

The broken line representations of a spray nozzle, a triggering apparatus, and a container closure in FIG. 7, and of internal support structure in FIGS. 4 and 6, are for purposes of illustration only and form no part of the claimed design.
